UNITED STATES PATENT OFFICE

2,367,291

PORTABLE BRIDGE

Robert G. Le Tourneau, Peoria, Ill., assignor to
 R. G. Le Tourneau, Inc., a corporation

Application September 22, 1941, Serial No. 411,829

5 Claims. (CL. 14—1)

This invention relates in general to a bridge or overpass structure, and in particular the invention is directed to a portable and sectional bridge arranged so that the sectional parts or spans of the structure may be transported in knocked-down or separated condition to the point of use and there assembled in bridge form.

One of the objects of this invention is to provide a portable and sectional bridge whose structure is of relatively low weight, and of such simplicity, that the several sections may be readily transported to the point of use and rapidly assembled, as is desirable, for example, if used for military or other emergency purposes; the bridge when assembled being capable of supporting relatively heavy loads.

Another object of the invention is to construct the separate spans of the bridge so that they are interchangeable as to their relative positions in the structure, which not only facilitates setting up of the structure, but makes possible the use of different length spans at any point in the bridge where necessary.

A further object is the provision of a unique supporting leg unit for each span; such unit when in use depending from a pivotal connection with the span and held rigid by adjustable knee-braces; these knee-braces being detachable at one end to permit the leg unit, together with the braces, to fold against the bottom of the span whereby the spans can be stacked one upon the other and thus transported.

It is also an object to arrange the spans so that the leg units can be attached adjacent either or both ends of such spans, and further to provide coupling or connecting means at the ends of the spans which are operative to couple adjacent span ends regardless of which ends of the spans are brought together; these features speeding the assembling operation of the legs on the spans, and the connection of spans of the bridge.

An additional object is to so construct the side beams or girders of the spans that in use they function not only as supporting members but also as wheel guards which prevent hub caps, fenders, and running boards from engaging the bridge, and prevent tires from being scuffed.

The structure of the spans further embodies a novel feature in the manner in which the box beam floor joists are connected with the side beams or girders; the use of connecting irons or straps being eliminated, and in addition the load on each joist is distributed or transmitted through the side girders to the other joists of the span.

A further object is to provide a structure of

the above defined type which is also admirably adapted for use as a general traffic overpass at street or highway intersections, so as to expedite and speed up traffic flow at such intersections.

5 These objects I accomplish by means of such structure and relative arrangement of parts as will fully appear by a perusal of the following specification and claims.

In the drawings similar characters of reference indicate corresponding parts in the several views:

Figure 1 is an elevational outline of a three section bridge embodying the invention.

Figure 2 is a plan view of a pair of spans detached from each other but in adjacent end to end relation.

Figure 3 is an enlarged fragmentary elevation, partly in section, of the assembled bridge structure.

20 Figure 4 is an end elevation of a span with the leg unit attached and in position of use.

Figure 5 is a side elevation of a ramp, detached.

Figure 6 is a fragmentary, enlarged, longitudinal section on line 6—6 of Fig. 2, showing the 25 mounting of a hinge ear and the bracing of the adjacent end portion of a span.

Figure 7 is a fragmentary transverse section on line 7—7 of Fig. 3.

Figure 8 is a transverse section on line 8—8 of 30 Fig. 3 showing the special taper extension initially used on hinge bolts to initially secure alignment of the hinge ears.

Figure 9 is a similar view showing one hinge bolt as secured in place.

35 Figure 10 is a cross section on line 10—10 of Fig. 3.

Figure 11 is a fragmentary transverse section of a modification and shows the side girders as connected to a special type of flooring.

40 Figure 12 is a longitudinal section on line 12—12 of Fig. 11.

Referring now more particularly to the characters of reference on the drawings, and particularly at present to Figs. 1 to 10, the structure in 45 general comprises a plurality of spans 1 hinged together at adjacent ends as at 2, and supported by leg units 3 which connect with said spans adjacent the hinges; the outer ends of the endmost spans extending over the bank B, for example, of a stream bed S which the structure bridges. To facilitate passage of vehicles onto the endmost spans, each of the latter is fitted with an approach ramp 4 hinged at one end onto the adjacent end of the span and resting at the 50 other end on the ground.

55

Each of the spans 1, which may be of any desired length, comprises transversely spaced side beams or girders 5 of box beam construction which in cross section are of trapezoidal form; the outer plate 5a being vertical, the top plate 5b of lesser width but greater thickness than the bottom plate 5c, and the inner plate 5d disposed at an upward and outward slope from its lower edge. The top plate 5b being thicker than the bottom plate 5c, there is no loss of strength even though the top plate is relatively narrow.

Box beam joists 6 extend transversely in longitudinally spaced relation and at their ends enter the side girders through inner plate 5d and project to a termination in abutment with outer plate 5a; the portion of the joists in girders 5 resting on bottom plate 5c. As so assembled, the joists and side girders are welded into rigid and unitary assembly; a transverse reinforcing plate P being secured between each joist and top plate 5b thereabove. By reason of the above arrangement, a cantilever action is had on both ends of the box beam floor joist, imparting more strength to each joist because the wheel load on one joist is distributed or transmitted through the side girders to all the other joists of the span.

Metal plate flooring 8 seats on and is welded to the joists and extends from end to end of the span between the inner girder plates 5d to which it is likewise welded. As the inner plates 5d of the side girders slope upward and outward, an effective wheel guard is provided, preventing wheel or body contact, as well as tire scuffing.

The several spans of the bridge are hinged together by means of the following:

Ears 9 of plate form are secured on edge against and depend from the bottom plate 5c of the side girders and project longitudinally beyond the ends of the latter; these ears being elongated and provided with an upstanding tongue 9a which projects through a slot into and is secured to the girder between the end joist 6 and a transverse reinforcing plate 7. In order that the spans can be connected together regardless of which ends thereof are brought together, a pair of spaced ears 9 project from opposite ends of opposite side girders, and the remaining opposite ends of such girders have a single ear disposed to project snugly between the pair of ears which will be adjacent and on the next span (see Fig. 2). These ears 9 are formed with matching holes 10 through which bolts 11 engage when the hinge ears are brought into position. In order to make the holes in the ears match correctly, and to facilitate placement of bolts 11, an elongated taper head 12 is threaded on each bolt; the shank of the bolt and head being of the same diameter. The bolt and taper head is driven through the holes in the engaged ears 9, the taper head providing a lead which assures proper alignment of the ears and ready placement of the bolt. When the bolt is in place, the taper head is removed and a conventional nut substituted therefor as shown in Fig. 9.

The ramps 4 are of much the same construction as the spans 1, except that at their free end portions and at the bottom they are beveled or feathered out for ground engagement, as shown at 13 in Fig. 5. Transversely spaced ears 14 project longitudinally from and in a plane below the inner ends of the ramps; such ears 14 being disposed for cooperative and bolted engagement with ears 9 on the adjacent end of the corresponding spans, being provided with horizontal base plates 14a which form bank or ground bearing members.

The spans of the bridge are supported by the leg units heretofore generally indicated at 3 in Fig. 1; such leg units being attached to the spans adjacent one end of the latter and always in the same corresponding position on the different spans. Each leg unit, as shown particularly in Figs. 3 and 4, comprises transversely spaced box beam legs 15 arranged in rigid, parallel relation by means of cross bracing 16. At their upper end the legs 15 are fitted with upstanding ears 17; there being a pair of such ears on one leg in spaced relation, and a single one of such ears on the other leg. The spacing of the legs and position of ears 17 is such that the latter cooperate with ears 9 on the corresponding span at either end; the pair of ears 17 straddling a single one of ears 9, and the single ear 17 projecting between a pair of ears 9; there being a pivot bolt 18 passing through matching holes in cooperating ears 9 and 17. The leg attachment holes in ears 9 are formed back of holes 19 for the span connecting bolts. A taper head, the same as head 12, may be used to lead bolts 18, and to align the holes of ears 9 and 17.

Knee braces 19, which include a turnbuckle 20, connect diagonally between the upper portion of each leg 15 and a bracket 21 secured on the bottom plate 5c of the corresponding side girder. These braces are connected at the ends to the leg and bracket by means of cap bolts 22 passing through eyes 23 on the ends of the braces and threaded into said legs and brackets; the underface of the head of bolts 23 being tapered and seating in a taper seat in the corresponding eye, as at 24. The bolts and eyes are thus self-aligning, and the bolt holes in the eyes can thus be made oversize to facilitate starting of the bolts into the threads, all as is shown in Fig. 10.

As the braces 19 are adjustable in length, they can be set to position the leg units vertical and compensate for any given slope of the spans; these braces being strong and effectively maintaining the leg units in place. When the bridge spans are disconnected for transport, the braces 19 are detached at one end and the leg units, together with said braces, are folded against the bottom of the spans and the latter stacked for transportation in such position.

It will be noted that brackets 21 are mounted on each span adjacent each ear or pair of ears 9, and that each ear has a hole 10 for a leg mounting bolt 18. By reason of this arrangement, a pair of legs may be mounted under any one span (particularly the center one), if desired, in which case no legs would be necessary on the adjacent ends of adjacent spans. It should also be noted that the adjustability of braces 19 is sufficient to enable them to extend from a leg mounted on the ear 9 of one span to the connecting bracket 21 on the adjacent span, instead of to the bracket on the same span as shown in the drawings.

The bridge is erected across a stream bed or the like by means of wheeled crane equipment such as shown in U. S. Patent No. 2,281,507. The sequence followed is for an initial span to be placed with one end on the bank B and the other end overhanging the stream bed S; the leg unit being on said other end and is swung down and secured in position by the knee braces. Thereafter the crane equipment, which carries the remaining spans, moves onto the first erected span, from their sets and connects the second span, then moves onto the second span and thus continues span erecting operations until the other bank of the stream is reached.

In Figs. 11 and 12, a span is shown with a special type of open flooring such as is known under the trade-name "I-Beam-Lok." This type of flooring is of relatively light weight and yet quite strong and in some instances may be used instead of the metal plates 8. As this open flooring, indicated at 25, includes a plurality of transverse I beams 26 in spaced, parallel relation, the joists 6 previously described are eliminated, and the flooring extends from side to side of the span and into the side girders 27 to a termination at the outer plates 27a thereof and resting on the bottom plates 27c; being secured to both thereof as by welding. The inner plates 27d of the side girders extend at an upward and outward slope from longitudinally extending shoes or strips 28 secured atop the flooring 25. Top plates 27b connect horizontally between the inner and outer plates to complete the side girders. Vertical reinforcing plates 29 are secured transversely within the side guides, being symmetrical to the interior thereof and engaging or seating on the upper edge of said I beams 26. A finish channel 30 connects the side girders 27 at their ends, and if necessary a longitudinal supporting beam 31 may be applied to the underside of flooring 25 centrally between the side girders.

While I have here shown the bridge as being made up of three spans, for purposes of illustration, it will be obvious that as many spans may be used as conditions may require, not only to span a given distance but to avoid, if desired, any considerable angle being formed between adjacent spans, and which would interfere with the desired smoothness of vehicle movement.

This latter factor is especially to be taken into consideration when the structure is erected as an overpass for general motor vehicle traffic at a street or highway intersection.

From the foregoing description it will be readily seen that I have produced such a structure as substantially fulfills the objects of the invention as set forth herein.

While this specification sets forth in detail the present and preferred construction of the structure, still in practice such deviations from such detail may be resorted to as do not form a departure from the spirit of the invention, as defined by the appended claims.

Having thus described my invention, what I claim as new and useful and desire to secure by Letters Patent is:

1. A portable bridge comprising a plurality of separate spans disposed in end to end relation, means detachably connecting adjacent ends of said spans together in rigid relation transversely, supporting leg units, and means foldably securing said leg units on and beneath certain of the spans for holding against the bottom thereof, and releasable means normally preventing folding of the

leg units from a span supporting position; said last named means comprising knee braces extending diagonally from the leg units to the span, said knee braces each including a turnbuckle assembly.

5 2. A portable bridge comprising a plurality of separate spans disposed in end to end relation, means detachably connecting adjacent ends of said spans together in rigid relation transversely, supporting leg units, means pivoting the leg units on certain of the spans for folding movement lengthwise and against the bottom thereof, and longitudinally adjustable braces connected between said leg units and said spans in releasable relation, said braces normally securing the leg units in rigid and supporting relation to the spans.

10 3. A portable bridge comprising a plurality of separate spans disposed in end to end relation, means detachably connecting adjacent ends of the spans in rigid relation transversely, supporting leg units for certain spans, said units including transversely spaced legs, means pivoting said legs at their upper end on the spans at transversely spaced points, and diagonal longitudinally adjustable knee braces extending lengthwise of the spans and pivotally connected between said legs and the spans, said braces normally maintaining the leg units in rigid supporting relation to the spans.

15 4. A portable bridge comprising a plurality of separable spans disposed in end to end relation, transversely spaced ears secured on the spans and projecting from the ends thereof, ears projecting from adjacent ends of the spans cooperatively engaging, means pivoting said cooperating ears together, a supporting leg unit for certain of the spans, said unit including transversely spaced legs, the transverse spacing of said ears and said legs being substantially the same, and means adapted to secure said legs at their upper ends in connection with the ears at either end of said certain spans; each leg unit including a diagonal knee brace secured to said unit intermediate its ends and an attachment element mounted 20 on the under side of said certain spans short of each end thereof, said knee brace being adapted for connection at its upper end to the adjacent one of said attachment elements.

25 5. A portable bridge comprising a plurality of spans in end to end relation, means detachably connecting adjacent ends of said spans, supporting legs secured in connection with certain of said spans, an approach ramp at the outer ends of the endmost spans, and means connecting adjacent ends of said ramps and endmost spans; said means including transversely spaced ears on the ramps, said ears being formed to provide ground engaging shoes.
